UNITED STATES PATENT OFFICE

125,937

DESIGN FOR A RECEPTACLE FOR CIGARETTES OR OTHER ARTICLES

Alfred F. Reilly, North Attleboro, Mass.

Application December 13, 1940, Serial No. 97,284

Term of patent 3½ years

To all whom it may concern:

Be it known that I, Alfred F. Reilly, a citizen of the United States, residing at North Attleboro, county of Bristol, and State of Massachusetts, have invented a new, original, and ornamental Design for a Receptacle for Cigarettes or Other Articles, of which the following is a specification, reference being had to the accompanying drawing, forming part thereof.

In the accompanying drawing:

The side of the article illustrated not shown is substantially plain.

The dominant feature of my design resides in the ornamentation of the cover of the article shown in full lines in the drawing.

I claim:

The ornamental design for a receptacle for cigarettes or other articles, as shown and described.

ALFRED F. REILLY.
